WEEDER

Joseph P. Banner, 2550 N. Venice, Tucson, Ariz. 85712

Filed Dec. 27, 1971, Ser. No. 212,840

Term of patent 14 years

Int. Cl. D8—03

U.S. Cl. D8—11

FIG. 3

FIG. 4

FIG. 1 is a perspective view of a weeder embodying my new design;

FIG. 2 is a front view of the weeder cutting head;

FIG. 3 is a rear view of the weeder cutting head; and

FIG. 4 is a side elevational view of the weeder.

I claim:

The ornamental design for a weeder, as shown and described.
